UNITED STATES PATENT OFFICE.

ALEXANDER R. WILSON, OF SEATTLE, WASHINGTON.

TYPE-DISTRIBUTER.

1,306,323.

Specification of Letters Patent. Patented June 10, 1919.

Application filed September 30, 1914. Serial No. 864,280.

To all whom it may concern:

Be it known that I, ALEXANDER R. WILSON, a citizen of the United States of America, and a resident of the city of Seattle, in the county of King and State of Washington, have invented certain new and useful Improvements in Type-Distributors, of which the following is a specification.

The invention has for its primary object 10 the provision of a machine or mechanism of the above character which is simple, durable in construction and efficient in operation. Other objects will be brought out as the description progresses.

15 Referring to the accompanying drawings, illustrating the preferred embodiment of my invention and wherein like characters of reference designate corresponding parts throughout the several views:

20 Figure 1 is a plan view of the invention, with parts broken away,

Fig. 2 is a view in side elevation thereof,

Fig. 3 is a fragmentary view in horizontal section of the type escapement and shuttle 25 mechanism,

Fig. 4 is an inverted view of the same on line 4—4 of Fig. 2, showing more particularly the rocker arm, valve and piston movements for the shuttle,

30 Fig. 5 is an enlarged fragmentary view in vertical cross section showing the piston for actuating the shuttle stops and delivery mechanism, with a fragmentary portion of the type fonts, taken on line 5—5 of Fig. 1,

Fig. 6 is a fragmentary plan view of the shuttle and delivery or feed mechanism.

Fig. 7 is a perspective view of the shuttle stop and delivery mechanism,

40 Fig. 8 is a fragmentary vertical cross sectional view through the key board taken on line 8—8 of Fig. 1.

Fig. 9 is a fragmentary horizontal sectional view taken on line 9—9 of Fig. 8, 45 showing more particularly the air conduits in plates leading to the cylinders which operate the shuttle and feed mechanisms.

Fig. 10 is a plan view of the transverse member or brace between the side frames 50 for supporting the oscillating cylinder and locking rods,

Fig. 11 is a fragmentary view in side elevation of the same,

Fig. 12 is a cross sectional view taken on line 12 of Fig. 10,

55

Fig. 13 is a fragmentary view in end elevation of the controlling handle, segment, and levers, for operating the locking and hoisting devices,

Fig. 14, is a view in side elevation of the 60 same, with parts broken away, showing more particularly the piston valves for the hoisting and oscillating cylinders,

Fig. 15 is a fragmentary cross sectional view of the machine with parts broken away 65 and showing more clearly the disposition of the various cylinders, and

Fig. 16 is a fragmentary horizontal sectional view taken on line 16—16 of Fig. 15.

To enable one to more readily grasp the 70 idea of the invention, a brief description of the scheme of the machine and its operation will be given and a more detailed description will follow thereafter.

The type lines to be distributed are placed 75 on a slide 1 and from this body of type lines 2, one type line 2' is lowered into a channeled holder 3. A suitable device 4 to be described, is provided for this purpose. A type escapement member 5 sliding between the lower end of the channeled holder 3 and a frame plate 6, forces the lowermost 80 type of the type line 2' into the shuttle 7, which latter slides back and forth in a slide-way 8 in the machine frame. A plurality 85 of superimposed fonts or type cases 9 are suitably arranged in the frame-work, and each is adapted to be brought into register with the slide-way 8 to have the type delivered to one or the other of its respective 90 pockets 9', it being understood, that there is a pocket 9' for each type character of each font. When a type is to be delivered to a certain pocket, the operator presses the key as 10' of a battery of keys 10 and there- 95 by permits air pressure to flow through a conduit 11 leading to a type arrester 12 which enters the slide-way 8 at a point adjacent the proper type pocket 9' and arrests the type at that point, so that by suitable 100 means to be described, the type is ejected into said pocket.

Referring now more specifically to the invention, 14 designates a base and 15 side plates, and mounted on the side plates is a 105 face plate 16 which is disposed at an angle

or slant, and upon this face plate, the type line slide 1 rests. One wall or flange 3' of the channeled type holder 3 extends over the type line slide 1 and the body of type lines 2 is drawn against said flange 3' by said slide 1, which has a flange 1' engaging behind the last type line of the body 2, and which slide itself is drawn along its slide-way 1'' by a cord or other flexible member 17, passing around pulley 18, journaled in the face plate 16, and then to a fluid cylinder 19 to be described.

Beneath the slide way for the type slide 1 is arranged a cylinder 20 on the face plate 16, and said cylinder is provided with a small cylinder 21 containing a piston 21 having connection with the type ejector or escapement member 5, which slides, as aforesaid, between the frame plate 6 and the said cylinder 20. At right angles to the member 5 is an arm 5' which at one time engages the projecting valve stem 22 and shifts its piston valves 24 and 25 to admit fluid pressure from the supply pipe 26 through one 25 or the other of ports 27, 28 to one or the other sides of the said piston 21 in cylinder chamber 21', the fluid pressure from said chamber 21' escaping through one or the other of ports 27, 28, as the case may be, to one or the other of the exhaust ports 29, or 30, according to which of the latter is exposed by its respective valve 24 or 25. Carried by the type ejector or escapement member 5 and sliding in a slot 6', is a block 31 35 which at one limit of its movement strikes the upper end of a lever 32 which is pivoted at 32' to the frame-work of the machine. The lower end of this lever 32 connects at 32'' to the stem 33 carrying the reversing 40 stop arm 34 and valves 35 and 36 which control the passage of fluid pressure to one or the other sides of the shuttle actuating piston 37, upon the stem 37'' of which latter, the shuttle 7 is carried. The valve 35 controls the exhaust port 35' and port 35'', the latter leading from one end of a cylinder 38 in which the valves 35, 36 operate, while the valve 36 controls the exhaust port 36', and port 36'', the latter leading from the opposite end of the cylinder 38. The ports 35'' and 36'' admit fluid pressure to one or the other sides of the shuttle operating piston 37 to reciprocate the same within the said slide-way 8.

55 The operation of the type ejector or escapement member 5 and shuttle is as follows: Fluid pressure being constantly supplied to pipe 26, upon depression of any one of the keys 10, setting of the valves 24, 25 as will be later described takes place, and the fluid pressure will then enter port 28 and get behind piston 21, forcing the same and the type ejector or escapement member 5 to the left, carrying the lowermost type 2' 60 of the lowered type line 2' with it and plac-

ing the same in the shuttle 7, where it is held and carried along the slide-way 8 as will be described. The movement of the member 5 to the left causes its block 31 to engage the upper end of the lever 32 and by 70 rocking the same to force the valves 35 and 36 to the right, covering port 35'' and uncovering port 36''. The fluid pressure flows through the latter and behind the piston 37, carrying the latter to the left and with it its 75 stem 37'' and shuttle 7, which latter travels along the slide-way 8, delivering its type as it goes, and eventually encountering the reversing stop arm 34, and through its contact with the latter, shifting the valves 35 80 and 36 to their former positions at the left, closing port 36'' and uncovering port 35'' so that the fluid pressure supplied through conduit 38 passes through said port 35'' into the cylinder chamber 37' and forces the piston again to the right, carrying with it the shuttle 7 back to position to receive another type.

The shuttle 7 comprises a base plate to which the valve stem 37'' is attached, and at 90 the left end of this base, extends upwardly a housing 7; which is closed on its front side and open at its rear side, as seen in Fig. 5. To the inner side of the inner front wall of the housing 7' is attached a leaf spring 40, its attaching end 40'' serving as a shoulder against which the type 2'' is placed by the ejector or type escapement member 5, and its free end 40'' yieldingly holding the type against said end 40' and against the inner wall of the front of the housing 7', as more clearly illustrated in Fig. 6. The upper and lower extensions 7'' of the upper and lower walls of the housing, on the rear side thereof, are respectively 105 provided with cams 41 and 42, arranged one above the other and having their inclined faces directed toward the closed front wall of the housing 7'; for a purpose to be described.

The mechanism for arresting the transportation of the type by the shuttle and for ejecting it therefrom into its respective pocket of the font to receive the same, consists of the following: Adjacent each font 115 pocket 9' is an arrester plate 44 frictionally reciprocating in a way 44', being resisted in its movement by the engagement of its integral struck up spring 44'' with the side wall of the way 44'. This plate is connected for movement with a piston 45 through a depending arm 46; whereby said plate 44 is, when the piston is operated, projected into the slide-way 8 into the path of the shuttle, its movement being arrested by contact 120 of its arm 46 with the stop 16' of the face plate 16 as shown in Fig. 5. It will be observed that the plate 44 enters the housing 7' of the shuttle, between the wall portions 7'' thereof, and its forked outer end 47 pro- 130

vides passage room in the nature of a notch 48 for the shuttle spring 40. The ends 47, while not obstructing free passage of the shuttle, project sufficiently far to engage the 5 type carried by the shuttle and to arrest further progress of said type. When so arrested, the shuttle moves on to engage its reversing stop arm 34 and thereby to be returned, but prior to its return, the said type 10 will have been deposited in its respective pocket 9'. Upon the arrester plate 44 is slidably arranged an ejector plate 50 which is normally held in the position illustrated in Fig. 7 by a spring 50', and at its outer 15 end the plate 50 is provided with a cross arm 51 having its ends 52 projecting above and below the same and said ends having beveled faces with which engage the shuttle cams 41 42 aforementioned. The piston 20 45, for each type arrester 44, has its outer end beveled as at 45', see Fig. 7, and with this beveled end engages a cam 45'' carried on the upper side of the base of the shuttle 7.

The operating of the type arresting and 25 ejecting mechanism is as follows: The operator depresses one of the keys 10, as the one 10', and fluid pressure is admitted from the valve of said key as will be described, and until specifically described, can be ob- 30 served in Fig. 8, and flowing into conduit 11 passes into the respective cylinder 53, see Fig. 5, containing said piston 45 of the arrester plate 44. It will be understood that each of said keys 10 has its respective con- 35duit 11 leading to its particular piston 45 of its respective type arrester plate 44, so that the type corresponding to the key de- 40 pressed will be delivered into its proper font pocket 9'. The piston 45 is then forced outwardly and consequently projects the ar- 45 rester plate ends 47 into the path of the type carried by the shuttle 7. The movement of the type being arrested, shuttle 7 moves onward and in its progress, its cams 41 42 en- 50 gage the projecting ends 52 of the ejector plate 50 and the latter is drawn toward the arrested type against the pressure of the spring 50' until the type is positively forced from beneath the holding spring 40 and de- 55 livered into its respective font pocket 9'. After the ends 52 pass over the cams 41, 42 the plate 50 is retracted to its original position by the spring 50'. As the shuttle progresses a little farther, its base cam 45'' 60 engages the beveled end 45' of the piston 45, forcing the same and its arrester plate back to their normal or inactive position, it being understood that this is made possible by the fact that the key-board key hav- 65 ing returned long since to its normal position, fluid pressure back of the piston 45 no longer exists.

Referring to the key-board mechanism, each key is provided with a stem 55 pro- 65 vided at its lower end with a piston valve

55' and returning spring 55'', and each key is arranged within a block casing 56 having passages 56' leading to a source of fluid pressure supply 57, and each key valve has its respective conduit 11, as shown in Fig. 70 70 75 and illustrated by a single example in Fig. 1, which conduit, as stated, for each key, leads to one of the said arrester plate cylinders 53. When a key is depressed, the fluid pressure flows from the main 57 75 75 through the passages 56' to whichever key is depressed, thence through the valve of said key and into its respective conduit 11.

To the left end of the valve chamber containing valves, 24, 25, a small port 59 is 80 shown entering said chamber, and this port is in communication with a conduit 60, and this conduit has communication through ports 61 with the interiors of all of the cylinder chambers of the arrester pistons 45, 85 as illustrated in Fig. 5. On the end of the valve stem 22, see Fig. 3, a third head 62 is provided, which serves as a piston to actuate the said valves 24 and 25. The object of this last mentioned construction is that 90 whenever a key is depressed to drop its type arrester plate 44 through the medium of its piston 45, the fluid pressure from whichever cylinder 53 is effected, passes through the port 61 in said cylinder upon said port 95 being uncovered by the piston 45 as the latter reaches the end of its stroke, and from said port 61, the fluid pressure flows through the conduit 60 and port 59 into the valve chamber of the cylinder 20 of Fig. 3. It 100 will be recalled that the type escapement member 5' last pushed the valve stem 22 to the left by contact therewith, thereby causing the valve 24 to uncover the port 27 to allow the fluid pressure to return the piston 105 21 to its right hand position as illustrated in Fig. 8, and also that the shuttle 7 has returned to its normal right hand position. While the piston 21 has returned to its right hand position, the valves 24 and 25 remain 110 at their left hand positions and for that reason the piston 21 cannot again operate to the left until the said valves 24 and 25 have been moved to the right again. To effect this, the fluid pressure coming through the 115 conduit 60 and port 59 gets behind the piston head 62 on the valve stem and shifts the valve to the right to again supply pressure to move the piston 21 to the left.

In this connection, it is very important to 120 remember that as soon as any of the keys is operated to select and drop its respective arrester plate 44, the same fluid pressure that operates the piston 45 for said arrester plate, passes on and shifts the valves 24 and 25 to 125 render the piston 21 and type escapement member 5 operable one time to the left and back to a position of rest at the right after shifting the valve stem 22 to the left. They remain at rest until another key is struck to 130

drop another arrester plate 44 and permit the fluid pressure from such operation to again shift the valve stem 22 to the right, when the escapement member 5 again becomes operable to the left and back again.

Reverting to the device 4, broadly referred to heretofore, and which is associated with the type slide 1, said device comprises a fluid pressure cylinder having a piston 4' having a 10' kicker foot 4" which, when the lower key 10" is depressed to supply fluid pressure through conduit 11', operates downwardly to force the end type line from slide 1 into the distributing channeled holder 3. The pack 15 or body of type 2 to be distributed is constantly drawn against the stop flange 3' of the holder by the cord 17 and its fluid cylinder 19.

The font shifting mechanism will now be 20 described. It is understood that the invention is not adapted to the distributing of type of only one style, but is capable of use with different styles of type, and it only becomes necessary for the operator to manipulate the lever 65 shown at the left hand side of the key-board 10 in Fig. 1, to select the proper font for the particular type being distributed and thereby bring such proper font into juxtaposition with the 25 shuttle 7 and the slide-way 8. To facilitate this, the fonts 9 are superimposed and are suitably secured to font slides 66, the securing means being either in the nature of rivets 66' (see Fig. 15) or of a detachable 30 nature to permit interchanging of the fonts. These font slides 66, which are on opposite sides of the fonts, reciprocate in ways 66" in the side frame members 15, and are held in said ways by an inverted channel bar 35 67 having depending right angular ends 67' secured at 67" to the side frame members 15, and against this bar 67, the lowermost font when the entire stack is lowered, rests, in 40 which position of the stack, the uppermost font registers with the way 8 to receive the type from the shuttle 7. As illustrated in Fig. 10, the ends 67' are slotted or cut-out to receive detent selector arms 68 which are 45 fixed on the outer ends of a rock shaft 69, which latter is journaled in and extends 50 longitudinally of the channel bar 67. The rock shaft 69 preferably comprises two sections, and upon their inner ends, or upon the central portion of the rock-shaft 69 as a 55 whole, is fixed a fluid pressure cylinder 70, which rocks in parallelism with the swinging selector arms 68 when the latter are actuated by means 71 to be described. The cylinder 70 contains a piston 72 having a stem 60 72' and a horizontal head 72" on the lower end of the said stem. Slidable within the lower ends of the selector arms 68 are locking pins 73 which are adapted to interlock 65 with selected ones of a series of apertures 73' formed in the inner faces of the font

slides 66. These pins 73 are entered into and retracted from engagement with the apertures 73' by links 74 which connect the said pins with opposite ends of the stem head 72" of the piston 72, and the links 74 themselves are under tension of springs 74' connected thereto and to the channel bar 67.

The font shifting handle or lever 65 is pivoted mid-way its length at 65' to an arm 65" and the latter is fixed to a tubular 75 rock shaft 75 containing a valve operating rod 76 pivoted at one of its ends at 75' to the lower end of the said lever 65 and being under the action of the spring 75" to normally place the said lever 65 in one or the other of the notches 77' of the segment 77, said segment being fixed at the left hand side of the key-board 1 to the machine frame-work. When the tubular shaft 75 is rocked by the swinging of the lever 65, the selector arms 68 for the font slide locking pins are actuated through the medium of a lever arm 78 fixed to said tubular shaft 75, link 78', lever arm 78" on a second shaft 79, and a second lever arm 79' on the same shaft 79, to which latter arm 79' the link 71 previously referred to connects. This link 71, it will be remembered, pivotally connects with the selector arms 68 to swing the same. The valve operating rod 76 within the said tubular shaft 75 connects with a sliding block 76' to which is connected by a pin 76" a cross head 80 on the outside of the rock shaft 75, and to this cross head is connected one end of a valve stem 81 carrying valves 82 and 83 operating within a chamber 84' of a casing 84 through which the rock shaft 75 passes and in which it is journaled. The valves cover and uncover exhaust ports 84^a and 84^b and conduits 85 and 86 to permit flow of fluid pressure from supply pipe 87 to the said pressure cylinder 70 of the font shifting mechanism. Upon the right hand end of the said tubular rock shaft 75 is a lever arm 88 which has a friction or slipping engagement or connection with the stem of a font raising valve 89 by means of a coupling 88^a, said valve stem being indicated by numeral 89^a. The said valve 89 is composed of two heads which control two exhaust ports 90^a in the cylinder 90, and further control the passage of the fluid pressure from the supply pipe 90^b to one or the other of the pipes 91, 92. As illustrated in Fig. 15, these pipes 91 and 92 connect 110 respectively with the upper and lower ends of font shifting cylinders 93. In Fig. 14, the pipes 91 and 92 are branched and each branch of pair 91 leads to the upper end of one of the cylinders 93, while each branch 115 of pair 92 leads to the lower end of one of the cylinders 93. Within the pair of cylinders 93 are arranged pistons 93' on stems 93", and the upper ends of these stems 93" are fixed or otherwise connected with the 120

125 130

lowermost font 9 to raise and lower the entire stack of fonts. To check the movement of the fonts and to ease the action thereof in general, an oil cylinder or dash 5 pot 94 is arranged between the two cylinders 93 and contains a perforated piston 94' on a stem 94", which latter is likewise connected with the lowermost font in the same manner as the stem 93". The oil contained 10 in the cylinder 94 is being compelled to flow through the perforations in the piston 94' causes the retardation of movement.

The operation of the font shifting mechanism is as follows: When the operator 15 wishes to bring a new font into position to receive the type from the shuttle, he pulls out the lever 65 at the left hand side of the keyboard, and in doing so pushes in the stem 76, slides the cross head 80 and moves the 20 valves 82, 83 to respectively uncover the exhaust port 84^a and conduit 85 permitting the fluid pressure from pipe 87 to flow through the conduit 85 to the upper end of the cylinder 70 to depress the piston 72 thereof.

25 This depression causes downward movement of the head 72" and the links 74 pull the lock pins 73 inwardly out of the locking apertures 73'. This occurs whenever the lever 65 is pulled out of one of the segment 30 notches 77'. The lever 65 is then turned toward the operator which causes the tubular rock shaft to be rocked, and this movement of said shaft 75 causes the link 88' to pull the valves 89 to the position illustrated in 35 Fig. 14 so that the fluid pressure flows through the branches of pipe 92 to the lower ends of font shifting cylinders 93 forcing the pistons thereof upwardly, moving the type fonts with them. This raising of the 40 fonts is materially retarded by the dash pot 94, at least to the extent that the operator has had time to release the lever 65 before the font shifting mechanism has moved the distance between any two of the locking 45 apertures 73'. The lever 65 having been released before the locking pins 73 reach the next succeeding locking aperture 73', the valves 82, 83 will have been reversed through the spring 75" and stem 76 in conjunction 50 with the cross head 80, and the direction of flow of the fluid pressure to the cylinder 70 will likewise have been reversed, so that the pressure is on the under side of the piston 72 and the locking pins 73, under 55 such pressure and that of the springs 74' will then have been set ready for entering whichever locking aperture 73' is selected for said pins 73 to enter. The selection of the desired apertures 73' for the locking 60 pins 73 to enter is made possible by the fact that the entire series of said apertures 73' is disposed in a plane at an angle to the longitudinal axes of the slides 66 and substantially in an arc with the shaft 79, (see 65 Fig. 15) substantially as the axis thereof.

In making the font selection, the operator shifts the lever 65 to the segment notch 77' corresponding to the desired font to be brought into position. This movement of the lever 65 causes the rock shaft 75 to move 70 as just described and through the medium of the lever arm 78, link 78', lever arm 78", rock shaft 79, lever arm 79' and link 71, the selector arms 68 with the locking pins set ready to enter an aperture 73' are moved into 75 line with the aperture 73' corresponding to the font selected. Meanwhile, the fonts are being raised by their pistons 93' and as soon as the desired font comes adjacent the delivery mechanism, the locking pins 73 will 80 be found to be adjacent the apertures 73' corresponding to that font, and said pins will promptly enter said apertures to lock the fonts at that point with the selected font in proper position. It will be understood that 85 the lever 65 may be moved in either direction to correspondingly rock the shaft 75, selector arms 68 and valve 89, and in either direction the action is the same, the locking pins being set ready to enter the selected 90 locking apertures 73' as the font stack is being slowly moved up or down by the pistons 93'.

The friction coupling 88^a is adopted to afford slippage between the link 88' and the 95 valve stem 89^a for the following reason. The extent of the throw of the lever 65 does not control the extent of the movement of the said valves 89, but merely controls the extent of movement of the selector arms 68, 100 yet the rocking movement of the shaft 75 caused by the movement of the lever 65, whether the latter is moved one or several notches 77', is utilized to shift the valves 89. If the lever 65 is moved more than one 105 notch 77', then slippage of the coupling 88^a takes place after the initial movement of the stem 89^a has taken place to set the said valves 89.

Briefly, the complete operation is as follows: The key 10" is struck to supply fluid pressure to cylinder 4 causing the kicker foot 4" to deliver a type line to the distributing channel holder 3. A key 10' of the set 10 is then depressed to supply fluid 110 pressure to its respective cylinder 53, see Fig. 5, causing the piston 45 to project the type arrester plate 50. Part of the fluid pressure passes through conduit 60 and port 59 into the valve chamber of the cylinder 115 20 of Fig. 3. The fluid pressure then shifts the valves 24 and 25 to the right hand position as shown in Fig. 3 permitting the piston 21 to be operated to the left by fluid pressure from pipe 26 passing through port 120 28. As the piston 21 moves to the left, the type ejector 5 correspondingly moves to force the end type 2" into the shuttle 7 which is at rest as shown in Fig. 3 ready to receive said type. As the type ejector 5 de- 130

posites the type in the shuttle 7, its block 31 engages the lever 32 and the latter is thereby moved to shift the valves 35—36 to the right, see Fig. 4, whereupon fluid pressure is admitted behind piston 37 to force the shuttle to the left to distribute the type. The type is intercepted and ejected by the projected type arrester and ejector 44, 50 respectively and delivered into its respective pocket 9' of the type case 9. At the time the block 31 operates, the valve lever 32 to operate the shuttle mechanism, the valve stem 22 is engaged by the arm 5' of the type ejector, and the valves 24, 25 moved to the left, causing fluid pressure from pipe 26 to pass through passage 27 to return the piston 21 and type ejector to the right hand position, where they remain at rest until another key of set 10 is struck. During the time the type ejector is being restored to its right hand position, Fig. 3, the shuttle 7 is moving to the left, distributing the type, and upon contact with the valve reversing arm 34 being also restored to its normal or right hand position of rest, as in Fig. 3.

What is claimed is:

1. A type distributing machine, comprising a shuttle, means for placing the type in the shuttle and means for operating the shuttle, type receivers, and means for arresting the type adjacent its respective type receiver and for entering it therein without arresting movement of the shuttle.
2. A type distributor, comprising a reciprocating shuttle, means for inserting a type therein, a series of type receivers in the path of the shuttle, means adjacent each type receiver for arresting the type and for entering it in the receiver without arresting movement of the shuttle, and means for selectively operating any one of said arresting means.
3. A type distributor, comprising a traveling shuttle, means for inserting a type therein, a series of type receivers along the path of the shuttle, a series of type arresters along the path of the shuttle and each arrester being associated with one of the type receivers, means for selectively moving any one of the arresters into the path of the type in the shuttle without arresting movement of the shuttle, and means associated with each arrester for entering the arrested type into its respective receiver.
4. A type distributor, comprising a traveling shuttle, means for inserting a type therein, a series of type receivers along the path of the shuttle, a series of type arresters along the path of the shuttle and each arrester being associated with one of the type receivers, means for selectively moving any one of the arresters into the path of the type in the shuttle, and means operated by the shuttle

for entering the arrested type into its respective receiver.

5. A type distributor, comprising a traveling shuttle, means for inserting a type therein, a series of type receivers along the path of the shuttle, a series of type arresters along the path of the shuttle, each arrester being associated with one of the receivers, means for selectively operating any one of the arresters to remove the type from the shuttle and enter it into its respective receiver without arresting movement of the shuttle, said first means being set into operation by the actuation of any one of the said arresters.

6. A type distributor, comprising a traveling shuttle, means for inserting type therein, a series of type receivers along the path of the shuttle, a series of type arresters along the path of the shuttle, each arrester being associated with one of the receivers, means for selectively operating any one of the arresters to remove the type from the shuttle and enter it into its respective receiver, a piston for operating the first means, a valve for said piston and adapted to be reversed by contact with the same, and means for initially setting said valve upon actuation of any one of the said arresters.

7. A type distributor, comprising a traveling shuttle, means for inserting type therein, a series of type receivers, a series of type arresters each associated with one of the receivers, fluid pressure means for selectively operating any one of the arresters to remove the type from the shuttle and enter it into its respective receiver, fluid pressure means for operating the first means, and a valve for controlling the movements of the last means, said valve being initially set by the fluid pressure from the first fluid pressure means upon actuation of any one of the type arresters.

8. A type distributor, comprising a traveling shuttle, means for inserting type therein, a series of type receivers, a series of type arresters each associated with one of the receivers, fluid pressure means for selectively operating any one of the arresters to remove the type from the shuttle and enter it into its respective receiver, a piston for operating the first means in two directions, a reversible valve adapted to be reversed by said first means, a piston on said valve for initially setting it, said piston being actuated by fluid pressure supplied from and upon actuation of any one of the first fluid pressure means.

9. A type distributor, comprising a shuttle, a series of type receivers along the path traveled thereby, means on the shuttle for holding a type, an arrester adapted to engage and remove the type from the shuttle, and means on the arrester operated by the

shuttle for entering the type into its respective receiver; said arrester being returned to its normal position by the shuttle.

10. A type distributor, comprising a shuttle, a type receiver along the path traveled thereby, means on the shuttle for holding a type, an arrester adapted to engage and remove the type from the shuttle, a normally retracted ejector on said arrester, and means whereby the ejector is projected by the shuttle to place the type in its receiver.

11. A type distributor, comprising a shuttle, a type receiver along the path traveled thereby, a yielding type holder on the shuttle, a type arrester adapted to be projected to arrest the type and remove it from the type holder, a normally retracted ejector on the arrester, and cam means on the shuttle adapted to operate the ejector to enter the type into its receiver.

12. A type distributor, comprising a shuttle, a spring type holder thereon, cams on the shuttle, a type arrester, a type ejector thereon normally retracted, a type receiver along the path traveled by the shuttle and adjacent the arrester, means for projecting the arrester to arrest the type and remove it from the spring holder, means on the ejector for engagement with one of said shuttle cams to project the ejector, and means on the arrester for engagement with the other shuttle cam for retracting the arrester.

13. A type distributor, comprising a shuttle, receivers along the path traveled thereby to receive the type therefrom, means for reciprocating the shuttle, means for placing a type into said shuttle, means for operating the shuttle controlled in its forward movement by the type placing means, and means at the end of the forward travel of the shuttle to be engaged by the latter to reverse the shuttle operating means.

14. A type distributor, comprising a shuttle, receivers for the type therefrom, means for delivering the type to the shuttle, a piston for operating said shuttle, a valve for admitting fluid pressure to opposite sides of the piston, means operated by the delivering means for moving the valve to admit fluid pressure to one end of the piston, and means carried by the valve for movement by the shuttle to reverse the valve and admit fluid pressure to the other end of the piston.

15. A type distributor, comprising a shuttle, receivers for the type therefrom, a shuttle operating piston, a valve and its stem, a lever connected with said stem and adapted to move the valve in one direction to admit fluid pressure to move the shuttle piston forwardly, an arm on said valve stem adapted to be engaged by the shuttle and to move the valve in the opposite di-

rection to admit fluid pressure to move the shuttle piston rearwardly, and type delivering means for placing type in the shuttle and being adapted to operate said lever.

16. In a type distributor, type delivery mechanism, a series of type receivers, means for shifting any one of said receivers into register with said delivery mechanism, said means including a fluid pressure motor, locking means, and means for setting the motor in operation and for actuating the locking means upon the desired receiver coming into register with the said delivery mechanism.

17. In a type distributor, type delivery mechanism, a series of type receivers shiftable to bring any one thereof into register with the delivery mechanism, locking means for securing the receivers in their shifted positions, a series of stops for coöperation with said locking means, and means for selectively engaging the locking means with any desired one of said stops.

18. In a type distributor, type delivery mechanism, a series of type receivers shiftable to bring any one thereof into register with the delivery mechanism, a shifting motor, locking means for securing the receivers in their shifted positions, a series of stops coöperating with said locking means, and means for operating the shifting motor and for selectively controlling the engagement of the locking means with any desired one of the said stops.

19. In a type distributor, type delivery mechanism, a series of type receivers shiftable to bring any one thereof into register with the delivery mechanism, a carriage for the receivers, a series of stops at an angle to the line of travel of the carriage, locking means, and means for shifting the carriage, and means for selectively engaging the locking means with any desired one of the said stops.

20. In a type distributor, type delivery mechanism, a series of type receivers shiftable to bring any one thereof into register with the delivery mechanism, a carriage for the receivers, means for moving the carriage, a series of locking devices on the carriage, the series being arranged at an angle to the line of travel of the carriage, and a pivoted locking member movable laterally to the line of travel of the carriage for selective engagement with any desired one of said devices.

21. In a type distributor, type delivery mechanism, a series of type receivers shiftable to bring any one thereof into register with the delivery mechanism, a shifting device, means for locking any receiver in register with the delivery mechanism, and a controller for setting the shifting device in operation in two directions selectively and

- for selectively locking any desired receiver in register with the type delivery mechanism.
22. In a type distributor, a type receiver shifter, comprising a receiver carriage, a fluid pressure device for reciprocating the same, means for locking the carriage at any of several points, a rock shaft, a handle thereon, means for actuating the locking means upon movement of the handle in one direction, and means for operating the fluid pressure device in either of two directions by movement of the handle in either of two directions at an angle to the direction of the first mentioned movement of the handle.
23. In a type distributor, a type receiver shifter, comprising a receiver carriage, a fluid pressure motor for moving the same in two directions, a rock shaft, means controlled by the rock shaft whereby the motor will be actuated in one direction or the other according to the direction in which the rock shaft is moved, lever for actuating said rock shaft, and means controlled by the lever for locking the receivers in any of the shifted positions.
24. In a type distributor, a type receiver shifter, comprising a rock shaft, valve mechanism actuated in two directions thereby, fluid pressure devices actuated in two directions according to and through the setting of the valve mechanism, a type receiver carriage actuated in two directions by said fluid pressure device, selective actuating mechanism for rocking the shaft, a valve controlled by the selective mechanism, a fluid pressure cylinder, said last valve adapted to supply fluid pressure to said cylinder to actuate its piston in two directions, locking means for the carriage movable into locked and unlocked positions by and according to the movements of said piston, a series of stops arranged at an angle to the line of movement of the carriage, and means actuated by the rock shaft for selectively moving the locking means into position for engagement with any desired one of said stops.
25. In combination, a type carrier, a type arrester, and means carried by the arrester and actuated by the type carrier to remove the type from the path of the carrier.
26. In combination, a type carrier, a type arrester, and means actuated by the carrier in passing to remove the arrested type from the path of the carrier.
27. In combination, a traveling type carrier, a type arrester and means for removing the type from the arrester, the type carrier containing means acting to successively remove the type from the arrester and then for removing the arrester to its inoperative position while passing said parts.
28. In a type distributor, a type carrier, means for placing a type therein, means for moving the type carrier over a definite route, selective means for removing the type from its carrier at any one of a series of points and means actuated by said carrier in passing to insert the type in a font.
29. In a type distributor, a type carrier, means for moving said type carrier over a definite route, type receivers disposed along said route, type arresters adapted to remove the type from the carrier and means carried by the type arresters and actuated by the carrier for placing the arrested type in a receiver.
30. In combination, a type carrier, a type arrester movable transversely of the path of the carrier, and engaging means carried by the carrier and arrester to move the latter by the former to shift the type laterally out of the path of the carrier.
31. A reciprocating type arrester, means for moving the arrester into type arresting position, and means actuated by the type carrier for further movement of the arrester to place the type into its storage pocket.

Signed at Seattle, Washington, this 1st day of August, 1914.

ALEXANDER R. WILSON.
